Primary Examiner — Kevin K Rudzinski*Assistant Examiner* — Clare Ann Gannon(57) **CLAIM**

The ornamental design for a TV cover, as shown and described.

DESCRIPTION

FIG. 1 is a perspective view of a TV cover showing my new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof; and,

FIG. 7 is a top plan view thereof.

In the drawing views, the broken lines represent portions of the TV cover that form no part of the claimed design.

1 Claim, 7 Drawing Sheets(56)
